UNITED STATES PATENT OFFICE.

JACOB KAUFMANN, OF PHILADELPHIA, PENNSYLVANIA, ASSIGNOR TO STEEL HEDDLE,
MANUFACTURING COMPANY, OF PHILADELPHIA, PENNSYLVANIA, A CORPORATION
OF PENNSYLVANIA.

HEDDLE-FRAME.

1,277,733.

Specification of Letters Patent.

Patented Sept. 3, 1918.

Application filed August 31, 1915. Serial No. 48,162.

To all whom it may concern:

Be it known that I, JACOB KAUFMANN, a citizen of the United States, residing at Philadelphia, in the county of Philadelphia and State of Pennsylvania, have invented certain new and useful Improvements in Heddle-Frames, of which the following is a specification:

My invention relates to heddle frames for looms and it has particular relation to an improved form of construction of the same. My invention contemplates a heddle frame which will be light yet strong and durable and in which fouling of adjacent frames in the loom will be reduced to a minimum. Heretofore most heddle frames have been made with the top and bottom rails of wood and in some instances these top and bottom rails have been connected at their ends by means of relatively thin flat metal end bars and in other cases the rails have been joined at their ends by wooden strips. Where the end bars have been made of thin flat metal it often occurs that the corners of adjacent frames will foul on each other by reason of the negligible surfaces of the end bars not affording any or a sufficient guide for each other. On the other hand where the end bars are made of wood the joints quickly become loosened because of the constantly shifting strains to which the structure is subjected when in use. The object therefore of my invention is to provide a heddle frame in which the defects of the two types of heddle frames above mentioned will be largely eliminated. A further object of my invention is to generally improve the construction of the heddle frame as will later appear.

The nature and characteristic features of my invention will be more readily understood from the following description taken in connection with the accompanying drawings forming part hereof, in which—

Figure 1 is an elevational view of a heddle frame embodying the main features of my present invention;

Fig. 2 is an enlarged fragmentary detail view, partly in section and partly in elevation, illustrating the construction of one of the corners of the frame;

Fig. 3 is an end elevation of the portion of the structure shown in Fig. 2;

Fig. 4 is a horizontal section of one of the end bars taken on the line 4—4 of Fig. 2; 55

Fig. 5 is a perspective view of a fastening or bracing member used in the structure.

Referring to the drawings, in the particular embodiment of my invention therein shown the heddle frame comprises top and bottom rails 6 formed of wood or similar material and connected at their ends by bars or strips 7 likewise formed of wood or similar material. The end bars 7 are 65 channeled or grooved on their outer sides as at 8 and in the groove thus formed there is mounted a reinforcing strip of thin flat metal which extends from top to bottom of the strip 7 and is bent over at each end as at 10 extending over the outer margin of the strip 6 to which the bent over portions 10 are secured by means of wood screws 11.

The strips 7 are secured or braced to the inner corners of the top and bottom rails 75 6 by means of bracing members 12 shown in detached perspective in Fig. 5 of the drawings. These bracing members are each formed from a strip of thin flat metal, one end of which is bent over as at 13 for seating the same securely in the groove 14 suitably located near the inner corner of the end rail 6 and the member 12 is secured to this portion of the rail 6 by means of a wood screw 15 which passes through a suitable aperture 16 in the strip 12. The fastening member 12 is also provided with a bent portion which forms a shoulder 17 in alignment with the end of the rail 6, and from the end of the shoulder 17 there extends a tongue 18 which passes through a suitable aperture 19 in the bar 7 and strip 9 and has its end portion 20 bent over on the outer surface of the metal strip 9 to securely fasten and brace the end bar 7 to 95 the inner corner of the rail 6.

The end bars 7 and similarly the strips 9 are suitably slotted for the mounting of the heddle bars 21 upon which the heddles 22 are mounted in the usual or any desired 100 manner. The ends of the heddle bars 21 are provided with apertures 23 for engagement by the ends 24 of the hook members 25 which are also provided with right angular extensions 26 mounted in suitable apertures in 105 the strips 9 and end bars 7, the bent ends

26 having a sufficient frictional engagement with said apertures 27 as to be normally retained therein.

It will thus be seen that there is provided 5 a light yet durable form of heddle frame in which the wooden end bars 7 are suitably reinforced by means of metal strips 9 which metal strips also afford a durable and convenient means of attaching the end bars 7 10 to the ends of the top and bottom rails 6. The metal strips 9 also provide hard bearing portions for the proper mounting of the heddle bars and their attachments in the end bars 7. Furthermore the end bars 7 are securely fastened and braced to inner corners of the top and bottom rails 6 so that the joints will be maintained secure notwithstanding the severe usage to which the structure is subjected in use.

20 Having thus described the nature and characteristic features of my invention what I claim as new and desire to secure by Letters Patent is:—

1. A heddle frame comprising top and 25 bottom rails, end bars connecting the ends of said top and bottom rails, said end bars having channels in their outer sides, metal reinforcing strips mounted in said channels and extending from end to end thereof and having their ends bent over and secured to said top and bottom rails, and fastening members mounted at the inner corners of the top and bottom rails comprising bent metal pieces having intermediate off set portions 30 forming substantial shoulders in alinement with ends of the top and bottom rails and having tongues extending through and engaging the metal reinforcing strips.

35 2. A heddle frame comprising top and

bottom rails, end bars connecting the ends 40 of said top and bottom rails, said end bars having channels in their outer sides, metal reinforcing strips mounted in said channels and extending from end to end thereof and having their ends bent over and secured to 45 said top and bottom rails, fastening members mounted at the inner corners of the top and bottom rails comprising bent metal pieces having intermediate off set portions 50 forming substantial shoulders in alinement with ends of the top and bottom rails and having tongues extending through and engaging the metal reinforcing strips, and heddle bars mounted in apertures extending through said end bars and metal strips.

55 3. A heddle frame comprising top and bottom rails, end bars connecting the ends of 60 said top and bottom rails, said end bars having channels in their outer sides, metal reinforcing strips mounted in said channels and extending from end to end thereof and having their ends bent over and secured to said top and bottom rails, fastening members mounted at the inner corners of the top and bottom rails comprising bent metal pieces having intermediate off set portions 65 forming substantial shoulders in alinement with ends of the top and bottom rails and having tongues extending through and engaging the metal reinforcing strips, heddle bars mounted in apertures extending through said end bars and metal strips, and retaining means for said heddle bars mounted 70 on said metal strips.

In testimony whereof I have hereunto 75 signed my name.

JACOB KAUFMANN.
